ROY R. PERRY, OF MOBILE, ALABAMA, ASSIGNOR TO LOTTIE T. LE GEAR, OF MOBILE, ALABAMA.

ELECTROPNEUMATIC PIPE-ORGAN ACTION.

Application filed January 26, 1923. Serial No. 615,089.

The present invention relates to improvements in electro-pneumatic pipe organ actions in which the conversion of the old tracker organ is accomplished at small cost and by a simple and compact mechanism wherein substantially instantaneous valve movement is had through the use of considerably shorter wind passages.

The invention consists in the arrangement, combination and grouping of the parts and in providing these parts in small units that may be individually removed from the organ without disturbing the companion mechanisms to enable the making of adjustments and the replacement and repair of parts quickly, conveniently and inexpensively.

A further object of the invention resides in the provision of an improved electro-magnet in which the core of the magnet is made hollow for the passage of the wind to thereby keep the magnet cool and to avoid the necessity for providing certain awkward instructions heretofore generally used.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 shows a vertical section, with parts in elevation, of an improved organ action constructed according to the present invention.

Figure 2 is also a vertical section taken on an enlarged scale on the line 2—2 in Figure 1 and with the tracker valve chest removed.

Figure 3 is a view similar to Figure 1 but illustrating a double arrangement, and is a stop action for tracker organ.

Figure 4 is an enlarged fragmentary sectional view through the magnet and associated parts.

Figure 5 is a horizontal section taken on the line 5—5 in Figure 4.

Figure 6 is a view similar to Figure 4 showing the armature closed against the end of the core.

Figure 7 is a vertical section taken on the line 7—7 in Figure 4.

Figure 8 is a horizontal fragmentary section taken through the double valve and wind pouch, and

Figure 9 is a perspective view of the armature valve and its stem.

Referring more particularly to the drawings 1 designates generally the tracker valve chest having the bottom board 2, the rear board 3 and the front board 4 being removable through the screws or other fastenings 5. The tracker valve chest is closed by end walls in a well-known manner but as this construction is usual in tracker organs, it has not been illustrated particularly.

Within the valve chest are hinged valves 6 supplied in appropriate number for controlling the passages 7 in the channel board 8 and in the pipe board 9. Springs 10 are employed to hold the valves 6 closed.

In accordance with the present invention the parts beneath this tracker valve chest 1 may be removed and replaced by the mechanism described as follows:—The pneumatic chest 11 is situated beneath the tracker valve chest 1 and is secured in any appropriate manner within the organ action. The front board 12 and the rear board 13 of the pneumatic chest 11 are removably attached as by the screws or other appropriate fastenings

14 and 15 to the top board 16 and the bottom board 17 respectively of said pneumatic chest. This chest is kept under pressure 85 and contains a number of pneumatics 18 in accordance with the range of the organ or console. A tracker valve wire 19 is coupled between each valve 6 and a corresponding pneumatic 18, the attachment preferably being by the use of screw eyes 20 and 21 which are threaded directly into the wooden material of which the valve and top plate of the pneumatics are formed. The bottom plate of the pneumatic is also generally of wood 95 and the flexible part may be made of suitable leather or other fabric and attached between the two plates as by gluing or any other appropriate manner.

The interior of each pneumatic 18 is in communication with a valve chest 22 disposed beneath the bottom boards 17 of the pneumatic chest. This valve chest comprises a front board 23 and a rear board 24 which are erected at opposite edges of the bottom board 25. End walls 26 and 27 are shown in Figure 2 as closing the end portions of the

100 communication with a valve chest 22 disposed beneath the bottom boards 17 of the pneumatic chest. This valve chest comprises a front board 23 and a rear board 24 which are erected at opposite edges of the bottom board 25. End walls 26 and 27 are shown in Figure 2 as closing the end portions of the

valve chest and similar end walls 28 and 29 are shown for the pneumatic chest. The walls are preferably attached or joined together at suitable places by screws or other desired fastenings which admit of the ready dismemberment of the chest. In the bottom beards 17 of the pneumatic chest 11 are numbers of openings or perforations 30 which communicate with the channels or 10 passages 31 made vertically through the upper portion of the front boards 23. These passages 31 communicate at their lower ends with transverse ports 32 which open through the board 23 and place the channels 31 in 15 communication either with the interior of the valve chest 22 or the outside atmosphere as controlled by the double valve arrangement shown. This double valve arrangement comprises a pair of valves 33 and 34 20 mounted upon a valve stem or wire 35 which passes axially through the port 32, lying in a horizontal direction and having free play through the guide 35 which is suspended from the board 36. This board 36 is ex- 25 tended upon opposite sides of the board 23 and screws or other fastenings are provided to hold this board to the bottom boards 17 of the pneumatic chest, and an appropriate block 37 being interposed between the board 30 36 and the bottom boards 17, the block 37 having screws or other fastenings 38 by 35 which it is attached to the front board 23 from the inside of the valve chest. Screws or other fastenings 39 pass upwardly 40 through the board 36, block 37 and take into the bottom board 17.

The board 36 at its outer end provides a support for the pouch or pocket board 40 having the hollow pockets 41 closed by the 45 leather or other flexible diaphragm 42 which are glued or otherwise secured to the interior face of the board 40. The leather or other button surrounds the valve stem 35' and prevents the tearing out of the fabric or leather material of which the diaphragm is made.

By reference to Figure 8 a view of the construction of the valves 33 and 34 will be rendered more apparent. Each valve preferably consists of a seating disc 46 of leather, 50 although other material may be used, a second intermediate disc 45 of felt or the like compressible material and a backing disc 46, such for instance as a fiber disc possessing rigidity and durability. These two valves 55 are secured against relative movement upon the stem 35' and they are adapted to alternately close against opposite mouths of the port 32 so that when one valve is closed the other is open. In this connection compare 60 the positions in Figures 1 and 8.

Now the interiors of the pouches 41 are in connection through tubes or wind conductors 47 with chambers 48 in the base portion of the front board 23. A vent tube 49 is inserted through this portion of the front

board and is arranged coaxial with the hollow core 50 of an electro-magnet. See in this connection Figure 6, wherein the windings of the magnet are indicated at 51 as being confined by fiber heads 52 and 53, the former of which lies against a brass plate 54 fitted against the inside face of the front board 23 and forming a support for the core 50 of the magnet which projects into the lower portion of the chamber. A metal disc 55 is positioned to vibrate between the inner ends of the vent tube 49 and the adjacent end of the core 50 and the disc constitutes an armature attracted to the core when the magnet is energized and it thus forms a valve for shutting off the supply of wind from the valve chest 22 to the chamber 48 or for closing the vent 49. As shown to advantage in Figure 9, the valve or armature disc 55 carries a stem 56 of wood or other suitable material to one end of which it is affixed as by a nail, screw or other fastening 57. The stem is of the form of a cross as viewed from the end thereof or is provided with flanges or circumferential channels to 90 permit the free passage of the air through the hollow core 50. The lead wires for the core 50 are indicated at 58 and 59 and these extend to the console for operation through the keys in a well known manner. 95

It will be noted in connection with the electro-magnet construction that, by the employment of the hollow core 50, a passage is provided directly in the structure of the magnet allowing the wind to pass therethrough and to have a cooling effect on the coils. At the same time the magnet is restricted to fewer parts and it is no longer necessary to drill three or more small holes through the brass plate 54 or magnet base 100 to allow the wind to enter the pouch.

It will be further appreciated that the organized device is extremely simple in form and is compact being constructed in sections as shown in Figure 2. Each of these sections is composed of six pneumatics, six valves and six magnets and the sections or units thus built up are mounted side by side in the organ action or frame and they may be removed individually from the organ 110 without requiring the disassembly of other parts. The sections or units are very small and may be readily held in the hand and the walls are so constructed and the parts so relatively arranged and disposed that access may be easily had to the interior and parts may be removed and replaced, or repaired without the requirement for tearing down the whole section. It will moreover be understood by those skilled in the art that 115 the device is provided to take the place of the old heavy tracker key action without having to discard the tracker valve and valve chest which is the most expensive part of the organ to build. The present improvement 120 125 130

therefore entails a large saving and enables the conversion to be accomplished very much more quickly.

The improved action as herein described is especially designed for the old tracker action organ, but it can be used in making an electro-pneumatic action organ out of a tubular-pneumatic action organ. It can also be used in the building of any modern electro-pneumatic organ manufactured today and possesses many features of simplicity in the grouping of mechanical and material parts that would recommend it either in the form shown in the drawings, or in slight variations thereof, for use in numerous instances where older types of organ are to be converted or where new organs are to be built. The improved action can be manufactured with less material, less machinery and consequently at a less cost than other actions, and practically every means for adjustment is accessible from the exterior.

Now in the operation of the action, the electro-magnets are energized from the console in a manner well known. The closing of the circuit through the coils 51 of an electro-magnet causes the core 50 to become magnetized and to attract the disc 55. The disc will thus become closed against the adjacent end of the core as shown in Figure 6, the magnetic attraction being in excess of the wind pressure within the valve chest 22. The wind is thus cut off from the chamber 48 and as a result also from the pouch or pocket 41 and moreover this pouch is placed in communication with the outside atmosphere through the vent tube 49 which has become uncovered by the movement of the disc 55 against the magnet core. There is always a pressure within the valve chest 22 bearing against the inner face of the valve 34 and when the pressure within the pouch or pocket 41 is thus allowed to fall, the valve chest pressure on the valve 34 will promptly close this valve against the inner mouth of the port 32 causing the companion valve 33 to be opened or moved to the position shown in Figure 8. The wind within the corresponding pneumatic 18 in the pneumatic chest 11 above will thus have a means of escape to the atmosphere down through the channel 31 and through the opened valve 33. The pneumatic pressure within the chest 11 will act upon the pneumatic 18 to effect a quick collapse of the same, and collapsing, the pneumatic 18 will exert a downward pull upon the tracker valve wire 19 to cause an opening of the connected tracker valve chest allowing the wind within the tracker valve chest 1 to get into the passage 7 and to the pipe corresponding with the key at the console.

When the key is released the circuit through the electro-magnet will be interrupted or discontinued and the disc 55, being no

longer held by strong magnetic attraction to the end of the hollow core 50 will be blown by the action of the wind within the valve chest 22 against the inner end of the vent tube 49, closing this tube and allowing the wind to circulate about in the chamber 48 and up into the pouch or pocket 41. The diaphragm 42 will thus be distended and the valves will be shifted back to the normal position indicated in Figure 1 where the valve 33 is closed against the outer mouth of the port 32 thus cutting off escape of the air from the pneumatic 18 to the atmosphere. The inner valve 34 is open placing the pressure within the valve chest 22 in connection with the pneumatic 18 and this pressure will inflate the pneumatic, being in excess of the pressure in the pneumatic chest 11. The tracker valve wire 19 will be released and the pressure within the tracker valve chest 85 and the cooperation of the spring 10 will restore the tracker valve 6 to a closed position.

The action will be substantially instantaneous and the response at the pipes will be quicker because of the relatively short distances traveled by the wind.

Now referring more particularly to Figure 3, a slight modification is herein shown in which the valve chest 60 is of increased size and has front and back walls 61 and 62 which are constructed substantially alike both having ports 63 and 64 and chambers 65 and 66. The two valves 67 and 68 control the port 63 in the wall 61; while similar valves 69 and 70 operate in conjunction with the port 64 in the opposite wall 62. Pouches or pockets 71 and 72 are provided in conjunction with the valves and communicate by tubes 73 and 74 respectively with the chambers 65 and 66. Two electro-magnets 75 and 76 are carried within the valve chest 60 and they operate to control the action of the valves and the supply of air or its release to and from the pouches in a manner already described. The top board 77 is provided with a continuous channel 78 communicating at opposite ends with the channels 79 and 80 in the upper parts of the walls 61 and 62. A partition 81 extends down into the center of the channel 78 in order to divide the channel and to lead the air separately from opposite sides to pneumatics 82 and 83 which are disposed on end and are connected by wooden brace 84 so that when one pneumatic collapses the other expands. In other words the valves 67 and 68 control a supply of air to the pneumatic 82 and the release of air therefrom and in a similar manner the opposite valves 69 and 70 having like effect on the other pneumatic 83. The pneumatic 82 is coupled to an arm 85 pivoted to the lower end of the lever 86 fulcrumed intermediately upon a bracket 87 and extending up and through a top slide 88 which moves within the pipe board and has

an opening 89 to register with the pipe opening 90 in the pipe board.

The operation of this device is as follows:—

- 5 To reverse, or close stop, is to open electrical connection on stop-on magnet 75 and close connection on stop-off magnets 76. When connection is broken at console, by reversing the movement of stop tab, the circuit is closed through the stop-off magnet 76. This attracts its armature disc and allows the pouch 72 to be vented to the atmosphere, the valve 69 closing and the valve 70 opening to permit a collapsing of 10 the pneumatic 83. On the other hand the magnet 75 is deenergized and consequently the pouch 71 is filled with air and the valve 68 is open allowing the wind pressure to get into the pneumatic 82 and expand this 15 pneumatic. This action causes the movement of the lever 86 and the lever shifts the stop slide 88 so as to cause registry between the opening 89 and the pipe passage 90. The energizing of the magnet 75 and the deenergizing of the magnet 76 will cause the pneumatic 82 to be vented and the opposite pneumatic 83 to be expanded and the lever 86 and slide will be moved in an opposite direction 20 to cut off the communication with the pipe passage.

The improved action will be installed at the end of each chest swell, great or choir. As many wooden or metal braces as may be required are used to support the action. The 35 action is designed to fit between the main upright frame or chest support faces and can be attached just underneath tracker organ chests. This action will be the full length of the organ for which it is designed.

40 It is obvious that various changes and modifications may be made in the details of construction and design of the above specifically described embodiment of this invention without departing from the spirit thereof, such changes and modifications being restricted only by the scope of the following claims.

I claim:—

1. An electro-pneumatic organ action comprising in combination with a valve chest 50 and valves therein, a pneumatic chest separate from the valve chest, pneumatics in the pneumatic chest, connections between said pneumatics and the valves, a second valve chest independent of said first valve chest and said pneumatic chest, means for removably securing said second valve chest to a wall of said pneumatic chest, said pneumatic chest having wind passages opening through a wall thereof and leading from 55 the pneumatics, said second valve chest having short wind passages arranged to register and communicate with said wind passages of the pneumatic chest and opening to the interior of the second valve chest and the 60 atmosphere, valve means to control communication of the pneumatics with the second valve chest and the atmosphere, and means to operate the valve means.

2. An electro-pneumatic organ action comprising in combination with a pneumatic chest having pneumatics therein, a valve chest having a removable valve board at the front thereof, said valve board having an air passage therein for communication with 70 a pneumatic in the pneumatic chest and opening through one side of the valve board into the valve chest and through the other side of the valve board into the atmosphere, a duplex valve mounted on the valve board 75 for alternately closing said air passage at opposite sides of the valve board and having a stem, a pouch board brace mounted on the valve board, a pouch mounted on the brace and connected to said duplex valve stem, 80 said valve board having a second air passage therein opening through the opposite side thereof and communicating with the pouch, and an electro-magnetic valve carried by the valve board for controlling said second air 85 passage to inflate and exhaust the pouch and operate the duplex valve.

ROY R. PERRY.
